UNITED STATES PATENT OFFICE.

JOSEPH B. KAUFMANN, OF MOUND RIDGE, KANSAS.

WINDOW SCREEN.

Application filed May 18, 1925. Serial No. 30,022.

This invention relates to closures broadly, but has particular reference to a window screen, or a screen door, which types of closures are used in warm weather.

5 The improvement is directed more particularly to what may be termed a fly escape, that is a device which is provided to allow flies to escape from the room, and to obviate the necessity of employing fly traps, fly paper, and the like.

It has been observed that when a fly has obtained a full meal, he flies to the window or door in an attempt to escape. The provision of a screen, or screen door to prevent 15 the entrance also operates to prevent such escape. I have therefore evolved and produced a novel screen which will allow flies to escape from the room and will at the same time practically eliminate the entrance of 20 an appreciable number of flies from the outside.

The particular improved construction for obtaining this result will become apparent from the following detailed description and 25 the accompanying drawing.

In the accompanying drawing forming a part of this application, and in which like numerals are employed to designate like parts throughout the same:

30 Figure 1 is a fragmentary outside view of the upper portion of a window screen equipped with the improved escapes.

Figure 2 is an enlarged detail sectional view showing the construction more plainly.

35 Figure 3 is a section taken approximately upon the plane of the line 3—3 of Figure 2.

Figure 4 is a view like Figure 3 showing a slightly different embodiment of the invention.

40 Referring to the drawing in detail, the reference character 1 designates one bar of a window screen, screen door, or the like, which in order to adapt it for the invention, is provided with a recess opening through 45 the outer and bottom faces, and forming what may be designated as a pocket 2. From Figure 2 it will be noted that this pocket flares downwardly to the entrance of the flies. Cooperating with this pocket is a 50 substantially U-shaped or channel shaped member which is fitted onto the bar 1 from the outside. The top flange 3 (see Figure 3) thus contacts the top of the bar, the bottom flange 4 contacts the bottom of the bar, and 55 the intermediate portion 5 bears against the

outer face of the bar and closes the corresponding face of said pocket. In this connection it should be noted that the pocket in addition to being flared downwardly has its inner wall 6 (Figure 3) curved outwardly, and leading to a restricted escape hole 7 in the plate 5. Moreover, the flange 4 is provided with an elongated entrance opening 8 registering with the entrance to said pocket. The flanges 3 and 4 may be set 60 into appropriate recesses formed in the bar 1 to render them flush with the surfaces of the bar, or they may be allowed to project as shown, for the thickness of the metal will hardly interfere with the effectiveness of 65 the device.

As before intimated, the invention is just as well applicable to a window as it is to a screen, door, or other similar closure. In Figure 4 I have shown the device revised 70 to accommodate a common glass window. In this figure the bar of the window frame is indicated by the reference character 9, the outer plate by the character 10, and the flanges by the characters 11 and 12. As in 75 the form first described the plate is provided with a restricted escape hole 12*, the flange 11 being substantially the same. The flange 12 however is bent as at 13 to provide an angular groove for reception of the window pane 14. The entrance to the pocket 15 in this instance is formed in the flange 12 and is restricted slightly by the presence of the angular bend 13.

80 From the foregoing description and drawing, it will be seen that I have evolved and produced a novel device which may be associated with conventional window screens, windows, doors, and the like in a manner to permit escape of flies from the interior of 85 the room. The device is such that it aids in the escape in that the pocket is formed in the top or side bars, and a shaft of light coming through the restricted escape hole tends to render the pocket readily visible, 90 and to attract the flies so that their escape will not be hindered. While the flies are permitted to escape rapidly, the restricted escape hole provided, serves to reduce the admittance of flies to a minimum. Not 95 only this, the device is such that its use is not rendered objectionable in rainy weather, because very little or no rain will enter therethrough. These and other features and advantages of the invention have 100 105 110

been made apparent from the description and drawing.

While the preferred embodiments of the invention have been shown and described, it is to be understood that changes coming within the field of invention may be resorted to if desired.

Having thus described the invention, what I claim as new and desire to secure by Letters Patent is:—

1. As a new article of manufacture, a fly escape device in the form of a channel shaped member having spaced flanges and an intermediate portion and also having an entrance opening in one flange and an escape aperture in said intermediate portion.
2. The combination with a frame adapted for use in a window or door opening and having a top bar with a recess in the underside and outer side thereof, of a channel-shaped member straddling the said bar and arranged over said recess and having an intermediate upright portion with an aperture in communication with the upper portion of the recess and also having upper and lower flanges, the lower flange provided with an aperture in communication with said recess at the lower end thereof, said aperture at the inner side of a bar carried by the frame.

In testimony whereof I affix my signature,

JOSEPH B. KAUFMANN.
